UNITED STATES PATENT OFFICE.

FRANK COONEY, OF DETROIT, MICHIGAN.

SHADE-ROLLER BRACKET.

Application filed October 9, 1925. Serial No. 61,442.

This invention relates to shade roller brackets, and particularly relates to brackets adapted to be mounted without the use of nails or the like.

5 It is an object of the invention to provide a pair of shade roller brackets adapted to be stamped from sheet metal at low cost, and adapted to be quickly and securely mounted upon a window frame without the use of 10 nails or the like, and without marring of said frame by prongs upon the brackets.

Another object is to provide a pair of 15 brackets of the described character that will be quite positively restrained from rotating with the shade roller, and which will each be positioned by a single integral supporting arm.

These and various other objects the 20 invention attains by the construction herein- 25 after described and illustrated in the accompanying drawing, wherein:

Fig. 1 is a vertical sectional view of the upper portion of a window frame showing the mounting of one of the improved 25 brackets thereupon.

Fig. 2 is a perspective view of said bracket.

Fig. 3 is a view similar to Fig. 1 showing the other bracket in its position of use upon 30 the frame.

Fig. 4 is a perspective view of said bracket.

Fig. 5 is a horizontal sectional view taken 35 on the line 5—5 of Fig. 3, showing how the bracket supporting arm is wedged into a face of the frame.

In these views, the reference character A 40 designates a window frame and B a shade roller adapted to be mounted in a well known manner in said frame.

The two brackets which embody the invention have the nature of substantially L 45 shaped sheet-metal stampings, each having a vertical portion C and upper and lower positioning portions D and E, projecting similarly rearward from the portion C, and an elongated gradually tapered tongue F projecting integrally rearward from the upper positioning portion and having its end beveled as indicated at F'. In the vertical 50 wall C of one of said brackets is formed a circular opening H to receive a journal pin I on one end of the roller B, and the corresponding wall of the other bracket has, ad-

jacent to one of its edges, a vertical slot J, 55 open at its upper end and over-hung slightly by one end of the positioning portion D, said slot receiving the usual flat tongue K upon the other end of the roller B.

In mounting said brackets, opposite bores 60 L are drilled in the upper portion of the frame A, their diameter being substantially equal to the intermediate width of the tongues F. The brackets are mounted by driving said tongues into said bores, until 65 the positioning portions D and E rest against the window frame. Since said tongues at their rear portions exceed the width of said bores, the rear edge portions of the tongues cut into the walls of the bores, 70 wedging the tongues firmly against removal, and at the same time restraining the brackets from rotation about said tongues. The shade roller is mounted upon said 75 brackets in the usual manner by insertion of the pin I in the opening H and engagement of the tongue K in the slot J.

The described roller presents the advantages that it may be very quickly installed, 80 that it is smaller and lighter than the brackets now commonly used, and that its stamped form is favorable to quantity production at low cost.

What I claim is:

1. A stamped sheet metal bracket comprising a U shaped body having a central portion formed with an opening for engagement by a shade roller, and having substantially parallel upper and lower portions projecting equally from said central portion, 85 and further comprising a tapering tongue integrally projecting centrally from said upper portion, having a blunt end and having a lesser width than said upper portion, and constituting the sole support for the 90 bracket.

2. A shade roller bracket having the nature of a sheet-metal stamping and comprising an intermediate portion vertically slotted adjacent to an edge thereof, and upper and lower seating portions integrally projecting from said intermediate portion transversely to the latter, the upper of said seating portions partially over-hanging the open upper end of said slot. 100

In testimony whereof I sign this specification.

FRANK COONEY.
